UNITED STATES PATENT OFFICE.

LOREN L. WHITNEY, OF HAMMOND, INDIANA, ASSIGNOR TO AMERICAN STEEL
FOUNDRIES, OF CHICAGO, ILLINOIS, A CORPORATION OF NEW JERSEY.

METHOD OF FORMING TURNBUCKLES.

Application filed July 24, 1924. Serial No. 727,914.

This invention relates to a new and improved method of making turnbuckles and more particularly to a method of forming such turnbuckles from a tubular blank by 5 means of forging operations.

The turnbuckle shown is particularly adapted for use with brake cylinder lever rods but it is to be understood that the process is adapted for the production of turnbuckles for any purpose. The turnbuckle includes a tubular member with an outer hexagonal portion whereby it may be turned and adjusted. The ends of the turnbuckle are thickened inwardly and threaded to afford 10 the connection to the two portions of the member the total length of which is to be adjusted. It is not desirable to have the turnbuckle thickened and threaded throughout its length.

15 It is an object of the present invention to provide a new and improved method of forming turnbuckles whereby they may be formed by a series of forging operations.

It is a further object to provide method of 20 this character adapted for commercial quantity production.

Other and further objects will appear as the description proceeds.

I have illustrated in the accompanying 30 drawings various steps in the operation together with the dies and plungers suitable for carrying out the operation.

In the drawings—

Figure 1 shows the form of blank used;

35 Figure 2 is an end view of Figure 1;

Figure 3 shows the blank after the first pass;

Figure 4 is an end view of Figure 3;

Figure 5 is a view after the second pass;

40 Figure 6 is an end view of Figure 5;

Figure 7 is a view of the completed turnbuckle after the third pass;

Figure 8 is an end view of Figure 7;

Figures 9 and 10 show the dies used in the 45 forging operation;

Figure 11 shows the first pass plunger;

Figure 12 is the second pass plunger;

Figure 13 is the second pass insert; and

50 Figure 14 is a view of the turnbuckle as assembled for application to the brake cylinder lever rod.

In the formation of the turnbuckle by the present process, a blank as shown in Figure 1 is first heated upon its middle portion.

The heating is localized to the middle portion which is the only part which it is desired to be formed under the first pass. The heated blank is then placed in the lower recess 22 of the die member 23 and the die member 24 is moved until its faces contact 55 with the corresponding faces of the die member 23. The recess 25 in the die member 24 encloses the other side of the blank 21.

The plunger 26 is now forced axially into the heated blank, the reduced portion 27 of the plunger entering the blank. It will be noted that the portion 27 is of such length that it has passed beyond the hexagonal portion 28 of the recess 22 and corresponding portion 29 of the recess 25 before the shoulder 30 of the plunger 26 engages the end of the blank. The portion 27 of the plunger prevents inward deformation of the blank and the heated portion of the blank which is located opposite the hexagonal portions 28 and 29 of the recesses is forced outwardly into these portions when the shoulder 30 of the plunger engages the blank. The blank is now in the form shown in Figure 3 with the hexagonal gripping portion 31 formed 70 thereon.

It is allowed to cool and then one end of the blank is highly heated by local application of heat. The insert 32 shown in Figure 13 is now substituted in the die 23 for the insert 33 shown therein. The corresponding insert is substituted for the insert 34 of die 24. As clearly shown in Figure 13 the insert 32 is provided with a recess 35 which corresponds to the semi-circular portion of the die recess 90 36. The insert placed in die 24 is similarly provided with a recess corresponding to the semi-circular portion of the die recess 37.

After having one end heated the blank is now placed in the upper recess in die 23 with 95 the heated end towards the left or open end of the recess. The hexagonal portion 31 is fitted into the hexagonal portion of the recess and the unheated end of the blank fits into recess 35 in the insert 32. The die 24 is now brought against the die 23 and the blank is completely enclosed. The plunger 38 shown in Figure 12 is now brought axially against the heated end of the blank. The reduced portion 39 of the plunger enters the opening 100 in the blank and the shoulder 40 bears against the end of the blank. It will be noted that the portion 39 of the plunger 38 is of a

smaller diameter than the reduced portion 27 of the plunger 26 used in the first pass. Referring to Figure 5, the plunger portion 39 equals in diameter the reduced bore 41 of 5 the turnbuckle. When thrust against heated end of the blank, the shoulder 40 upsets the metal and forces it inwardly against the plunger 39 forming the blank, as shown in Figures 5 and 6, with the reduced securing 10 portion 41 formed.

The blank is now allowed to cool and its opposite end is locally heated. It is then placed in the upper recess 36 of die 23 with the insert 33 in position, as shown in Figure 9. The 15 completed cold end of the turnbuckle now abuts against the insert 33. The die 24 is brought against die 23 and plunger 38 is again thrust inwardly. This forms the heated end 20 of the blank in a manner similar to that in which it has previously formed the other end and the turnbuckle now assumes the completed form shown in Figures 3 and 8. The 25 reduced bore portions 41 and 42 are next threaded by a suitable machine and the turnbuckle is ready for use.

It will be understood by those skilled in the art that it is necessary to handle the blanks and partly completed turnbuckles by means 30 of mandrels or holders. When the blanks are placed in the dies, the mandrels extend out from the dies through the recesses 48. It will be obvious that, if desired, a three pass die may be used instead of the two pass die shown and in this case the necessity for the 35 inserts 32, 33 and 34 will be avoided.

In Figure 14 the completed turnbuckle 43 is shown as applied to a brake cylinder lever rod connecting the two end portions 44 and 45 which threaded shanks enter the ends of 40 the turnbuckle. The nuts 46 and 47 are brought up against the ends of the turnbuckle to lock in place and they cover the threaded 45 portions of the shank. The turnbuckle is obviously capable of use in other applications.

45 I claim:

1. The method of forming turnbuckles or the like from a tubular blank which comprises heating the central portion of the blank, enclosing the central portion of the blank in dies 50 limiting its outward expansion, applying means to the inside of the blank whereby its inward deformation is prevented and applying force longitudinally of the blank whereby

the middle portion is forced outwardly against the dies. 55

2. The method of forming turnbuckles or the like from a tubular blank which comprises heating the central portion of the blank, fitting the blank into dies enclosing it on all sides and one end, the dies being adapted to 60 permit outward deformation of the central portion, applying means to the inside of the blank whereby inward deformation is prevented, applying force to the unenclosed end of the blank whereby the central portion is 65 forced outwardly against the die, applying heat to one end of the blank, placing it in enclosing dies, applying force to the heated end whereby it is deformed inwardly and treating the other end in a similar manner. 70

3. The method of forming turnbuckles or the like from a tubular blank which comprises heating the central portion of the blank, fitting the blank into dies enclosing it on all sides and one end, the dies being adapted to 75 permit outward deformation of the central portion, applying means to the inside of the blank whereby inward deformation is prevented, applying force to the unenclosed end of the blank whereby the central portion is forced outwardly against the die, applying heat to one end of the blank, placing it in enclosing fixed dies, placing means within the heated end permitting a limited inward deformation, applying force to the heated end 80 whereby it is deformed inwardly and treating the other end in a similar manner. 85

4. Those steps in the method of producing turnbuckles or the like which include locally 90 heating a blank, upsetting said blank at the heated portion thereof to form a gripping portion, locally heating other portions of said blank and upsetting said portions in another direction from said first named upset portion to form thread receiving portions. 95

5. Those steps in the method of producing turnbuckles or the like which include locally upsetting said blank to form a gripping portion, locally upsetting other portions of said blank in another direction from said first 100 named upset portion to form thread receiving portions.

Signed at Hammond, Indiana, this 18th day of July, 1924.

LOREN L. WHITNEY.
